Primary Examiner — Ryan Harvey

(57) **CLAIM**

The ornamental design for a push up training equipment, as shown and described.

DESCRIPTION

FIG. 1 is a front perspective view of a push up training equipment showing my new design;

FIG. 2 is a rear perspective view thereof;

FIG. 3 is a front plan view thereof;

FIG. 4 is a rear plan view thereof;

FIG. 5 is a left side elevational view thereof;

FIG. 6 is a right side elevational view thereof;

FIG. 7 is a top elevational view thereof;

FIG. 8 is a bottom elevational view thereof;

FIG. 9 is an exploded perspective view of the push up training equipment; and,

FIG. 10 is a perspective view of the push up training equipment where the push up training equipment is in a folded position.

The broken lines in the drawings depict portions of the push up training equipment that form no part of the claimed design.

1 Claim, 10 Drawing Sheets
